DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpora-
tion of New Jersey

Application December 15, 1934, Serial No. 54,442

Term of patent 14 years

To whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic features of the design reside in parallel bands or stripes consisting of a plurality of individual stitches arranged in diagonal series in raised relation to the base fabric resulting in a continuous spiral-like or intertwined rope effect.

I claim:

The ornamental design for a textile fabric or similar article of manufacture substantially as shown and described.
